Application October 1, 1932. Serial No. 635,736

4 Claims. (Cl. 132—83)

Our invention relates to talcum or face powder containers of the type known as compacts, and more particularly to compacts for loose powder.

Compacts comprise a shallow compartment for powder which is normally closed by a lid or cover, which may have a mirror, and in which the powder is exposed when the lid is open so that it may be taken up by a puff. The powder may be contained in the compact either as a loose powder or as a cake of compressed or molded powder. The latter form of powder is less desirable for many reasons than the former. The loose powder has, however, the disadvantages that when the compact is opened, the powder tends to fly about and spill, not only losing powder but creating an unsightly condition. Constructions to prevent this loss and spilling of powder have heretofore been ineffective or have interfered with the application or use of the powder.

An object of the present invention is to provide a "compact" or powder container in which the loose powder will at all times be confined and prevented from freely spilling, while permitting it to be taken up by a powder puff or other means.

In our invention the opening of the container is covered or closed by a foraminous, porous or reticulated diaphragm, the openings or pores of which are sufficiently small or restricted to prevent the outflow of powder, but which may be enlarged by pressure to permit the passage of powder in small quantities to the outer face of the diaphragm where it can be taken up by a puff or other powder applying means. The diaphragm may be of any material having sufficient resiliency or elasticity to permit the openings to open and contract to such extent as to permit a small amount of the powder to pass therethrough when enlarged and to hold the powder when contracted. This material may be of suitable fabric of the required resiliency or elasticity or of a porous resilient material such as rubber.

The various features of the invention are illustrated in the accompanying drawing, in which—

Fig. 1 is a perspective view of a compact or container embodying a preferred form of the invention.

Fig. 2 is a sectional view of the compact taken on line 2—2 of Fig. 1, and

Fig. 3 is an enlarged or magnified plan view of a portion of the compact and the diaphragm spanning an opening therein.

In the accompanying drawing, the invention is shown as applied to a flat container 10 having side walls 11 of any desired shape, a circular wall

being shown by way of example. The container opens upwardly. In the example shown in the drawing the opening extends to the edge of the wall 11, but it will be understood that an opening of any desired size may be used.

In our invention, the opening is spanned and closed by a diaphragm 12 having openings 13 sufficiently small, when the diaphragm is in its normal position indicated in Fig. 2, to retain the powder and prevent it from spilling out of the container even when the latter is inverted. The diaphragm 12 may be held in place at its periphery by any suitable means, for example, between an outer ring 14, closely fitting the wall 11 of the container and having a protecting edge flange, 65 and an inner ring 16 having a rounded flange 17 at its upper edge.

The peripheral area or margin 18 of the diaphragm may be held between the rings 14 and 16 solely by friction or compression or additionally by a cementing material such as shellac or resin or glue. The outer ring 14 should fit the edge of the opening or the inner surface of the wall 11 to prevent escape of the powder from the container, but is preferably removable.

The diaphragm 12 may be made of any suitable material that will permit the openings 13 to vary sufficiently to grip and hold the powder when in its normal position and to release a small quantity when distorted. A diaphragm of rubber having small openings is preferred. The openings may be made mechanically either before or after vulcanization, or a porous rubber may be employed. The required porosity may be imparted by incorporating or generating air or gases or removable fillers prior to or during vulcanization. For example, a porous rubber may be made by beating to a froth a latex of rubber or similar gums in which has been incorporated a small proportion of sulphur, a frothing agent 90 such as soap, an accelerator, preferably an ultra-accelerator and, if desired, fillers and colors. The froth is then spread to a thin sheet, set by drying or coagulating, and vulcanized. The thickness of the sheet may be about that of ordinary card- 95 board or thinner.

The size of the openings or pores may vary. They may be about the size of pin holes, or smaller, or hardly perceptible when not distorted. They then hold any powder in them and prevent powder from passing through. If an area of the diaphragm, such as indicated at 19 in Fig. 1, be stretched by a finger or by the rubbing of a powder puff, the openings enlarge, releasing the powder and, if pressed downwardly onto a 110

- mass of powder, permit a small amount of the latter to flow upwardly through the diaphragm. When released, the diaphragm contracts, closing the pores and gripping any powder that may be contained therein. A small quantity of powder may be caused to pass through the diaphragm by tapping it, which simultaneously opens the pores and causes a draft through them that carries a small quantity of powder as a dust.
- 10 The container may be provided with a cover 20 and may provide space for a powder puff 21. A mirror 22 may be provided and other accessories as desired.
- What we claim is:
- 15 1. A compact comprising a shallow powder container presenting a relatively large dispensing area, and a diaphragm covering such dispensing area composed of elastic, flexible, porous material of a character normally to retain the powder, but to permit dispensing thereof, upon distortion by a wiping pressure thereagainst.
- 20 2. A compact comprising a shallow powder container presenting a relatively large dispens-
- ing area, and a diaphragm covering such dispensing area having a substantial extent of porous distortable material of a character normally to retain the powder, but to permit dispensing thereof upon distortion by a wiping pressure 80 thereagainst.
3. A compact comprising a shallow powder container presenting a relatively large dispensing area, and a diaphragm covering such dispensing area having a substantial extent of distortable material with multiple minute passages therethrough of a character normally to retain the powder, but to permit dispensing thereof by a wiping pressure 85 thereagainst.
4. A compact comprising a shallow powder container presenting a relatively large dispensing area, and a diaphragm covering such dispensing area having a substantial extent of porous rubber material of a character normally to retain the powder, but to permit dispensing 90 thereof by a wiping pressure thereagainst.
